UNITED STATES PATENT OFFICE.

HARRY M. HART, OF ST. LOUIS, MISSOURI, ASSIGNOR TO UNITED SHOE MACHINERY COMPANY, OF PATERSON, NEW JERSEY, A CORPORATION OF NEW JERSEY.

HOLDDOWN.

1,138,856.

Specification of Letters Patent.

Patented May 11, 1915.

Application filed June 9, 1913. Serial No. 772,628.

To all whom it may concern:

Be it known that I, HARRY M. HART, a citizen of the United States, residing at St. Louis, in the State of Missouri, have invented certain Improvements in Holddowns, of which the following description, in connection with the accompanying drawings, is a specification, like reference characters on the drawings indicating like parts in the 10 several figures.

This invention relates to lasting machines and particularly to a new and improved hold-down finger and mounting therefor. In order to meet certain well understood 15 commercial conditions, among which the demand for shoes with flexible soles is important as is also the need to use cheap materials due to the advancing price of leather, it has become the practice to use for inner- 20 soles certain comparatively thin and flexible stock which has been found sufficiently durable to give satisfaction in moderate priced shoes if the shoes are properly lasted and sewn. In order to secure the proper lasting 25 of the shoe it is necessary to prevent the thin and flexible innersoles from crumpling at the channel and allowing the feather to be pushed back out of alinement with the edge of the last bottom. There is also danger of 30 the channel lip or rib being crushed inwardly and distorted during the lasting operation by the pressure of the stiff and bulky materials composing the toe tip against the rib. This danger is particularly great upon 35 the outer side of the toe portion of the shoe. If the shape of the rib has been retained by the use of a suitable support at its inner side, which also should prevent buckling of the innersole at the channel, it is possible for the 40 welter to sew a firm narrow inseam at the proper distance inwardly from the edge of the last around the toe of the shoe to the advantage of the appearance and durability 45 of the shoe. While it has been proposed to provide a plate having an edge face which would fit against the rear face of the rib and support the same during the lasting operation, it has been found expensive to provide a separate plate for each style of shoe being 50 manufactured, as becomes necessary if the rib is to be adequately supported by this means.

An object of the present invention is to provide a holddown finger having a toe 55 plate which will readily and automatically adapt itself to various shapes of toes, in- cluding both rights and lefts and will afford the necessary support for the innersole rib about the toe portion of the shoe and particularly along what is the outer side of 60 the toe of the shoe as worn.

An important feature of the invention is found in a novel construction of a multi-part hold-down plate which is adaptable to different shapes of toes and which preferably, by the act of bringing it into operative position upon the shoe and against the rear face of the innersole rib, is caused automatically to assume the proper shape required by the contour of the rib of the particular 70 toe being treated. In the construction herein shown by way of illustration as embodying this invention the hold-down plate is composed of lateral parts which are movable independently longitudinally of the shoe, 75 the said parts being so connected to their supporting finger that they may also move independently of each other about vertical pivots which permit angular movement of the plates in the plane of the last bottom. 80

As a further feature of the invention, the mounting of the plates comprises mechanism whereby the plates, after they have automatically assumed an approximate abutting relation to the lip of the innersole, are 85 caused, by further forward pressure of the plates against the rib, to separate and adapt themselves to the particular toe or apply additional pressure along the sides of the toe. The connection between the parts of 90 the plate and their supporting finger preferably comprises links which are pivoted respectively to the said parts and at a common point upon the finger. The links therefore form a toggle which may be arranged 95 with the angle between the links directed rearwardly or toward the heel of the shoe so that pressure of the links against the lip when applied through the support will cause the toggle to straighten and effect a lateral 100 movement of the mid portion of the parts constituting the hold-down plate. Preferably and as shown in the selected embodiment of the invention, the connection of the hold-down plate to its supporting finger 105 comprises a universal joint which enables the plate to assume an even bearing against the face of the innersole whatever may be its inclination to the horizontal. Taking the lasts as they come in a shoe factory, 110 there is considerable variation in the spring of the last; that is, in the lengthwise incli-

2
nation in different styles of the bottom of the forepart relatively to the plane of the heel seat, and there is also variation in the curvature of the forepart. It is therefore
5 important that means be provided which
will enable the hold-down to be adjusted to
provide the usual firm clamping action over
the ball of the shoe and at the same time to
bring the hold-down plate into firm engage-
10 ment with the insole at the toe. In the illus-
trated construction the hold-down finger is
formed as an integral forward extension
from the shoe clamping member that is to
engage the shoe over the ball of the last and
15 the hub of this clamping member, which
with the finger and plate constitute the hold-
down foot, connects the foot to the carrier
which is arranged to extend transversely
across the shoe bottom. To permit adjust-
20 ment of the hold-down foot to the spring of
the last, the hub of the clamping member
is pivoted to the hold-down carrier for
movement about a horizontal axis extend-
ing transversely of the shoe. Furthermore,
25 to retain the finger and its plate against
angular displacement upwardly relatively to
its carrier, ratchet means is provided be-
tween the foot and the carrier which pre-
vents movement of the hold-down plate up-
30 wardly away from the shoe but permits
movement thereof toward the shoe in case
the spring of the last renders such move-
ment necessary. The ratchet means may be
released for adjustment of the arm in a con-
35 trary direction.

Figure 1 is a perspective view of a hold-
down embodying this invention as applied
to a bed lasting machine; Fig. 2 is an en-
larged perspective view of the hold-down
40 showing more clearly the relation of the
hold-down plate to the rib or lip of the
insole; Figs. 3 and 4 are plan views illus-
trating different adaptations of the hold-down
plate; Fig. 5 is a detail of the construc-
45 connecting the hold-down plate to its sup-
port; Fig. 6 is a view of a feature of the
invention applied to a narrow hold-down
finger.

The hold-down supporting and operating
50 means is substantially that shown and de-
scribed in British Patent No. 19,512/11 and
comprises a post 2 carrying a block 4 in
which is mounted for sliding adjustment
55 transversely of the shoe a carrier arm 6.
The block can turn and the carrier swing
about the longitudinal axis of the post 2 to
bring the carrier 6 into and out of operative
60 position over the shoe. The forward end of
the carrier 6 is formed as a stud or bearing
8 to engage an opening in a supporting arm
or finger 10, the finger being held upon the
stud by a suitable nut 12 and washer as
65 shown. Beneath the bearing 8, the finger
10 is formed with a toothed or roughened
work engaging face 14 which rests against

the ball portion of the innersole when the
finger is in operative position and, as a
clamping member, holds the forepart of the
shoe rigidly against the toe rest 16 located
beneath the shoe.

The forward end of the supporting finger
10 is downturned and formed as a ball 18,
Fig. 5, which engages a socket 20 formed in
a connecting member 22 having a flange 24.
The ball is held in place by a retaining cap
26 threaded upon the member 22. Links 28
and 30 are halved together and pivoted by a
screw stud 32 upon the under face of the
flange 24 against which they may bear and
against which they may be clamped, if de-
sired, by the screw stud 32 so that they may
form, operatively, a part of the connector
22. To the free ends of the links 28 and 30
are pivoted at 34, 36, Fig. 2, the segmental
parts 38, 40 of the hold-down plate. The
parts of the plate when considered together,
as best shown in Fig. 4, present an oval out-
line which is preferably egg-shaped, one end
of the plate having a greater curvature than
the other. From this figure it will be seen
that the more pointed end of the plate is
adapted to fit behind the rib of pointed-toed
shoes, and that by reversing the plate upon
the ball 18 the opposite or more rounded end
of the plate may be used for a somewhat
broader toe. As represented in Fig. 4, the
links 28 and 30 are so positioned that pres-
sure of the finger 10 toward the toe tends to
hold the parts of the plate together instead
of forcing them apart, as occurs when the
links are positioned as in Fig. 3. The ar-
rangement of the links shown in Fig. 4 is
particularly adapted for use with narrow
toes where it is desired to afford a very firm
support for the rib at the extreme point of
the toe. Referring again to Fig. 3 it will be
noted that this form of plate, when brought
into contact with the rib at the toe portion
of a shoe by swinging the carrier 6 about the
post 2, will automatically swing about the
ball 18 and the pivots 32, 34, 36 and assume
a bearing relation with the rib at the toe
portion, and in the case of a pronounced
right or left form will come into bearing for
a considerable distance along the outer or
more curved side of the toe, as indicated at
42. It will also be apparent that further
pressure of the supporting arm 10 toward
the toe of the shoe will cause the links which
form a toggle to straighten and force the
segments 38, 40 apart, thereby causing them
to fit more closely against the rib along the
sides of the toe. To prevent excessive strain
upon the links due to the downward pres-
sure brought to bear upon the hold-down
plate, the flange 24 is provided which over-
lies the links and distributes the pressure
over the greater part of their length. More-
over, if as described the screw stud 32 is so
formed as to hold the link of the toggle
130

firmly against the flange 24, the parts 22, 24, 26, 28, 30, 32 will act as a single member forming an evener or equalizing device between the parts 38, 40 of the hold-down plate to cause the plates to be moved equally and oppositely longitudinally of the shoe, and such operation of the device is to be understood as within the present invention.

In order to adapt the hold-down for use upon lasts of varying spring, the finger 10 is pivoted as described upon the bearing 8 and in order that both the teeth 14 on the finger 10 and the hold-down plate may be brought with considerable pressure upon the bottom of lasts having varying lengthwise inclination of the forepart, means is provided between the finger 10 and the carrier 6 for preventing rotation of the arm in a direction to carry the plates 38, 40 away from the shoe. As shown, ratchet teeth 44 are provided on the rear face of the finger 10 and a coöperating spring pawl 46 is mounted in the carrier 6 and acts to hold the arm 10 in depressed relation against the last bottom. A thumb pin 48 is provided on the catch 46 by which it may be released when it is desired to move the finger 10 in a clockwise direction. In Fig. 6 is shown the above described ratchet mechanism as applied for controlling the angular position of a hold-down finger of a simple type analogous to the spring finger now in common use.

Having described my invention, what I claim as new and desire to secure by Letters

Patent of the United States is:—

1. A hold-down foot comprising a clamping member to engage the shoe over the ball of the last, and a forwardly extending finger having a toe plate pivoted thereto near the center of curvature of the toe for lateral positioning movement, said plate comprising members which are also angularly movable relatively to fit differently shaped toes.

2. A hold-down foot comprising a clamping member to engage the shoe over the ball of the last, and a forwardly extending finger having a toe plate pivoted thereto near the center of curvature of the toe for lateral positioning movement to fit differently shaped toes and comprising side members 38, 40 spaced apart and each separately pivoted for relative positioning movement.

3. A hold-down foot having a toe plate comprising lateral members connected by a toggle arranged to cause forward pressure applied through the toggle to force the said lateral members outwardly as well as forwardly.

4. A hold-down foot having a toe plate comprising lateral members mounted to turn about a common center located between said members and each about a separate center.

5. A hold-down foot having a toe plate comprising lateral members mounted to

turn about a common center near the center of curvature of the shoe toe and each about a separate pivot, said separate pivots being movable laterally toward and from the median line of the shoe.

6. A hold-down plate comprising laterally separated parts mounted for relative movement longitudinally of a shoe and for pivotal movement in the plane of the shoe bottom to enable the plate automatically to fit against the innersole rib of varying shapes of shoes.

7. A hold-down plate for lasting machines comprising separate parts adapted respectively to fit against the rib on opposite sides of the toe portion of a shoe, and supporting and operating devices for said plate whereby the parts of the plate will be caused to separate when the plate is forced against the rib at the toe.

8. A hold-down for lasting machines having, in combination, a hold-down plate, and supporting and operating means therefor, said hold-down plate comprising separate portions mounted for movement independently of each other longitudinally and laterally of a shoe.

9. A hold-down for lasting machines comprising a longitudinally divided hold-down plate, supporting and operating means therefor, connections between the support and the plate permitting reversal of the plate end for end in its own plane, and further connections permitting limited movement of the lateral halves of said plate in the same plane.

10. A hold-down plate comprising parts adapted respectively to fit against the rib on opposite sides of the toe portion of a shoe, and a device whereby one of said parts is moved equally and oppositely to the other longitudinally of the shoe to adapt the member to variously shaped toes.

11. A hold-down plate comprising laterally separated parts having the general outline on their outer edges of a shoe toe, said parts being mounted for relative movement longitudinally and laterally of the shoe to enable the said member to fit against the innersole rib along the outer side of both right and left shoes.

12. A device of the class described, having, in combination, a carrier, a hold-down foot having at one end a portion rigidly supported on said carrier for engagement with the ball portion of a shoe innersole to clamp the shoe against the toe rest and a forwardly extending portion, an evener pivoted to said forwardly extending portion for universal movement, and plates pivoted to said evener for movement in a horizontal plane, said plates being segmental in outline with one end of greater curvature than the other and being reversible end for end to present either end toward the toe of a shoe.

13. A device of the class described having, in combination, a carrier, a foot on the carrier, an evener on the foot extending transversely of the shoe, and plates mounted 5 on the ends of the evener for free movement in a horizontal plane and adapted to fit against the rib of the innersole on opposite sides of the shoe toe.

In testimony whereof I have signed my name to this specification in the presence of 10 two subscribing witnesses.

HARRY M. HART.
